UNITED STATES PATENT OFFICE.

EDWIN C. KEYES, OF ELYRIA, OHIO.

LEGGING.

Application filed August 6, 1921. Serial No. 490,311.

To all whom it may concern:

Be it known that I, EDWIN C. KEYES, a citizen of the United States, and a resident of Elyria, in the county of Lorain and State 5 of Ohio, have invented certain new and useful Improvements in Leggings, of which the following is a specification.

This invention relates to leggings, and more particularly to leather leggings for 10 protecting the lower limbs and feet of workmen from burns when working around blast furnaces and other steel mill plants, where sparks and molten particles of metal are likely to strike them.

15 One object of the present invention is to construct a legging for this purpose that will closely or snugly engage the limb and foot of the wearer so as to prevent sparks or metal falling behind the legging.

20 Another and important object is to provide a legging that will be constructed of such material that it will not be destroyed or damaged by sparks or hot metal striking it, and yet providing such material that will 25 be sufficiently flexible to adapt itself to the limb of the wearer without discomfort to him.

Still another object is to provide a legging having improved fastening means whereby 30 it may be fastened or unfastened in the shortest possible time, experience having shown that only a few seconds are necessary to fasten or unfasten a legging constructed in accordance with this invention.

35 The above and other objects will be brought out in the following specification and illustrated in the accompanying drawings, in which—

Figure 1 is a side elevation of a legging 40 embodying my invention, applied to the limb of a wearer.

Figure 2 is a view similar to Figure 1, showing the legging applied to a large limb.

45 Figure 3 is an elevation of the legging opened out to show the inside thereof.

Figure 4 is a top view of the reinforcing steel secured adjacent the flap edge of the legging, and showing the socket for the reception of the end of the reinforcing steel 50 secured along the other longitudinal edge of the legging.

Figure 5 is a side elevation of the lower portion of the steel shown in Figure 4.

55 Referring particularly to the drawings, the leg covering portion A and vamp portion

of my legging are formed integral and composed preferably of chrome tanned split leather cut in three pieces 2, 3, and 4, which pieces are sewed or otherwise secured together with the exception of the abutting edges of the pieces 2 and 4 which are left free to form a vertical or longitudinal opening to permit the legging to be secured around the limb of a wearer. The pieces 2 and 3 are so shaped at their lower ends that they form an integral vamp portion 5.

The abutting longitudinal edges of the pieces 2 and 4 along the legging opening are provided with stiffening or reinforcing steels 6 and 7, respectively, which are secured to the inner face of the pieces and covered by strips 8 and 9 of leather or the like which is sewed to the pieces 2 and 4.

The piece 3 of the legging is provided 75 at a point adjacent its longitudinal center and approximately intermediate the edges of the assembled legging with a third stiffening or reinforcing steel 10 which is secured thereto and covered with a strip 11 80 of leather or the like which is sewed to the piece 3.

The lower end of the steel 6 extends outwardly through the strip 8 and is sharpened or tapered as at 12 so as to fit within a socket 85 13 formed on or secured to the lower end of steel 7 and projecting outwardly through the piece 4 of the legging, thus forming a quick securing device for the lower end of the legging.

The upper end of the legging is closed 90 by a snap buckle of common design, composed of a tongue member 14 secured to the piece 4, and an apertured receiving member 15 secured to the piece 2. The member 15 is provided with a plurality of tongue receiving apertures so as to provide an adjustable closure for the upper end of the legging.

A buckle 16 is secured at the lower end 100 of the piece 2 adjacent its free edge and is adapted to receive a strap 17 which has its one end secured to the lower end of the piece 3 adjacent the steel 10. The strap 17 is adapted to be secured in the buckle 16 105 to hold the legging down close on the foot of the wearer.

A flap 18 is secured to the under side of the piece 4 along its free longitudinal edge, and is of gradually tapering width 110 from top to bottom. The flap 18 is adapted to extend under and beyond the free edge

of the piece 2 when the legging is adjusted to the limb of a wearer to effectively close the joint made by the edges of the pieces 2 and 4, thus preventing any foreign matter 5 such as sparks or hot metal entering said joint.

A rim like top member or band 19 is secured around the top of the leg covering portion A and is so cut and formed that 10 its top edge is contracted to a considerably less diameter than the top of the leg covering portion A of the legging, and therefore, it will snugly engage the limb of the wearer and effectively close the top of the legging,

15 To those familiar with steel mill operations, the advantages of this improved legging will be readily apparent. The securing devices are such that it may be quickly fastened or loosened, which is an advantage 20 in case the wearer should become injured and it becomes necessary to remove his leggings. Another advantage and important improvement is the provision of the flap 18 and band 19 which effectively prevent 25 the passage of sparks or hot metal particles under or behind the legging, thus minimizing the danger of burns to the wearer.

While I have shown and described but 30 one specific embodiment of my invention in detail, I do not wish to be limited thereto, since various changes in material, combination and design of parts may be made without departing from the spirit of my 35 invention as defined in the appended claim.

It will also be understood that the word "steel" as used in describing the reinforcing members 6, 7, and 10, is to be construed

to include other equivalent materials such as bone.

I claim—

A legging comprising a leg covering portion open at one side, and an integral vamp portion, said legging being composed of split stock leather, a single reinforcing steel 45 secured along each of the longitudinal edges of said leg portion, the lower end of one of said steels being adapted to fit within a socket on the other of said steels to secure the lower end of said legging together, a 50 third reinforcing steel extending longitudinally from top to bottom of said legging at a point approximately intermediate the longitudinal edges of said legging, means for adjustably securing the upper end of said legging together, a flap secured to the inner face of said legging along its one longitudinal edge an appreciable distance so as to protect the leg of the wearer along said opening, and a non-elastic top rim-like portion secured to the inner face of said leg portion adjacent its upper edge and extending upwardly beyond said leg portion an appreciable distance, said rim-like portion having its upper edge contracted to a considerably less diameter than the top edge 65 of said leg portion so as to snugly engage the limb of the wearer and prevent the entrance of foreign matter such as hot metal and sparks between the legging and the 70 limb of the wearer, substantially as shown and described.

In testimony whereof, I have hereunto set my hand.

EDWIN C. KEYES.
